UNITED STATES PATENT OFFICE.

CORTEZ MERRILL, OF OELWEIN, IOWA.

BOTTLE STOPPER.

1,416,227.

Specification of Letters Patent. Patented May 16, 1922.

Application filed January 27, 1921. Serial No. 440,443.

To all whom it may concern:

Be it known that I, CORTEZ MERRILL, a citizen of the United States, residing at Oelwein, in the county of Fayette and State 5 of Iowa, have invented certain new and useful Improvements in Bottle Stoppers; and I do hereby declare the following to be a full, clear, and exact description of the invention, such as will enable others skilled 10 in the art to which it appertains to make and use the same.

This invention relates to new and useful improvements in bottle stoppers and more particularly to what will be known 15 hereinafter as a cork or stopper particularly adapted for use on thermos bottles and the main object of the present invention is the provision of a cork or stopper which is not only used for closing the bottle but 20 constructed so that the same can be used as a cup or receptacle for receiving the contents of the bottle so that the owner of the bottle can readily consume the contents from the cup portion of the stopper.

25 Another object of this invention is the provision of a bottle stopper including an aluminum, metallic or composition body provided upon its exterior surface with a composition coating which will readily engage 30 the interior of a bottle neck when inserted therein so that the cork or stopper can be readily inserted within the neck of the bottle and remain in position until the owner of the bottle desires to remove some 35 of the contents thereof whereby the stopper can be quickly and readily removed from the neck of the bottle. It will also be noted that this composition arranged upon the exterior of the stopper forms a liquid-tight closure.

40 A further object of the present invention is the provision of a cork or bottle stopper having a hollow aluminum, metallic or composition body portion provided upon its exterior surface with a plurality of dove-tailed 45 ridges and having a coating of cork or rubber composition arranged over these ridges, the coating being pressed beneath the dove-tailed portions of the ridges so that the coating will be readily retained in position upon the exterior of the body.

50 With the above and other objects in view the invention consists in the novel features of construction, combination and arrangement of parts hereinafter more fully set

forth, pointed out in the claims and shown 55 in the accompanying drawings in which:

Figure 1 is a side elevation of a cork or bottle stopper constructed in accordance with my invention;

Fig. 2 is a vertical sectional view; and, 60

Fig. 3 is a bottom plan view of the metallic body, a portion of the same being broken away and illustrated in cross section showing the application of the coating thereto.

In the construction of my improved cork 65 or stopper I provide a metallic body generally indicated by the numeral 1 which is preferably cup-shaped as shown in Fig. 2 and provided around its top edge with a reinforced flange 2. The body of the cup is 70 provided upon its exterior with a plurality of circumferentially arranged dove-tailed ribs 3. These dove-tailed ribs are not only arranged circumferentially of the side walls of the body, but also upon the bottom of the 75 same as shown in Fig. 3. It will be noted in Fig. 2 that the flanged portion 2 projects outwardly beyond the face of the ribs 3 and in order to form a smooth and unbroken surface upon the exterior of the body, a 80 coating of any desired composition may be applied thereto as shown at 4, said coating being forced into the spaces between the ribs 3 and as illustrated in Fig. 2, the outer rib at the bottom of the body member is provided with a plurality of inclined openings 85 as shown at 5 whereby the coating material can be readily pressed into these openings so that the coating material will be held in position upon the exterior of the body. 90

Attention is also directed to the fact that the circumferential ribs upon the bottom of the body of the cup are provided with radial extending openings 6 into which the coating or composition will be pressed so as to 95 assist the dove-tailed ribs in retaining the composition in position upon the body of the cup.

I wish it to be understood that any suitable material can be used in the construction 100 of the body of the stopper which forms the cup portion 7 and that any desirable composition can be used upon the exterior of the body such as a cork composition, rubber composition or the like and the entire cork 105 or stopper when finished may be of any desirable size to fit various types and sizes of thermos bottles and while I especially des-

5
ignite this cork or stopper as preferably used in connection with thermos bottles, it will be readily apparent that the same can be used in connection with any liquid container.

10 It is a well known fact that the contents of thermos bottles which are placed in the bottles in a heated state and during the cooling of the contents create a vacuum within the bottle which tends to draw the cork toward the interior of the bottle, and it will be noted that by providing the flange 2 at the outer or open end of the stopper this flange will engage the top of the neck of the bottle 15 and prevent the cork from being drawn inwardly.

I claim as my invention:

20 1. A bottle stopper including a hollow body member having an annular flange at its open end, a plurality of ribs arranged circumferentially of the body upon its side walls and bottom portion, the outer face of said ribs terminating short of the flange on

the body, and composition matter pressed into the body to a thickness of the space between the outer edge of the flange and the faces of the ribs to provide a smooth uniform surface.

2. A bottle stopper including a hollow cup-shaped body, an annular flange formed at its open end, a plurality of dove-tailed ribs formed circumferentially upon the exterior of the body, said ribs being disposed around the side walls and bottom of the body, the ribs on the side of the body portion terminating short of the outer face of the flange, and a coating of composition matter pressed onto the body and adapted to fill the space between the outer face of the flange and the outer faces of the ribs, portions of said ribs being provided with the transverse openings to receive the composition matter and retain the coating in its respective position upon the exterior of the body.

In testimony whereof I affix my signature. 45
CORTEZ MERRILL.
